UNITED STATES PATENT OFFICE.

WILSON W. BURSON, OF ROCKFORD, ILLINOIS.

KNITTING-MACHINE.

1,201,691.

Specification of Letters Patent. Patented Oct. 17, 1916.

Application filed March 25, 1912. Serial No. 685,930.

To all whom it may concern:

Be it known that I, WILSON W. BURSON, a citizen of the United States, residing in Rockford, in the county of Winnebago and State of Illinois, have invented a new and useful Improvement in Knitting-Machines, of which the following is a specification.

This invention relates to improvements in knitting machines and more particularly to that type of knitting machine disclosed in my Patent No. 996,059, issued June 27, 1911.

The objects of the invention are to provide means for causing the projecting and retracting or knitting cams to simultaneously assume an inoperative position, to provide automatically operated means for adjusting the knitting cams, to provide means for insuring the positive return of the needle jacks after the loop has been formed, and to provide means for securely holding the jacks in their retracted position when not operating.

My invention furthermore consists in the improvements in the parts and devices and in the novel combinations of parts and devices herein shown, described or claimed.

In the drawing forming a part of this specification, Figure 1 is a plan view of a knitting machine, showing my improvements applied thereto. Fig. 2 is a side elevation of the structure shown in Fig. 1. Fig. 3 is a plan view, upon an enlarged scale, showing the cam bar and the needle bed, parts of the structure being broken away to more clearly illustrate the invention. Fig. 4 is a plan view of one of the cam bars with parts broken away. Fig. 5 is an elevation of a part of the cam bar, showing the means for raising and lowering the cams. Fig. 6 is a transverse sectional view, taken on the line 6-6 of Fig. 4, and including parts of the knitting mechanism not shown in Fig. 4. Fig. 7 is a vertical sectional view, taken substantially on the line 7-7 of Fig. 5. Fig. 8 is a detail view, taken on the line 8-8 of Fig. 3. Fig. 9 is a plan view of a portion of the mechanism, comprising one member of the knitting cam and the adjusting member connected thereto. Fig. 10 is a sectional view, taken transversely of the needle bed, substantially on the line 10-10 of Fig. 2. Fig. 11 is a detail, sectional view of the lever for operating the dog which controls the position of the knitting cams and taken on the line 11-11 of Fig. 2. Fig. 12 is a partial, transverse section, taken on the line

12-12 of Fig. 2. Fig. 13 is another transverse sectional view, taken through the needle bed of the machine and showing the jack depressed. Fig. 14 is a diagrammatic view, illustrating the operation of one member of the cam on one of the needle jacks, showing the different positions assumed by the jack as the cam operates the same. All the views shown in Figs. 3 to 14 inclusive are upon an enlarged scale relatively to the scale used in Figs. 1 and 2.

In the drawing, 10 denotes the frame of the machine, on which are mounted the rotary pattern cylinders 11, suitably driven from a pulley 12. Adapted to reciprocate on ways 13 is a cross head 14, which carries the cam bars 15. Mounted on each cam bar 15 is a bar 16, pivoted at 17 to the cam bar, said bar 16 having secured thereto adjacent its free end a cam carrying block 18, which is 75 slidable up and down in a recess 19 in the cam bar 15. The bar 16 is normally pressed upwardly by means of a spring 20 and is limited in its upward movement by a stop 21 secured to the cam bar 15. The bar 16 is 80 guided in its up and down movements by means of a bracket 22 to which is secured a rotatable wheel 23, the latter being provided with an even number of ratchet points 24, and having also a number of cam faces 25, 85 the number of the latter being half the number of the ratchet points, each of said cam faces 25 being adapted to contact the wedge shaped cam member 26 secured to the bar 16. From the preceding description, it will be 90 seen that each second movement of the wheel 23 will cause a depression of the member 16, and hence the bar 16 will be alternately raised and lowered by the rotating of the wheel 23. The wheel 23 is automatically 95 rotated as desired by means of a pair of dogs or fingers 27 which are located respectively at each end of the needle bed, as shown more clearly in Fig. 3. Each of these dogs 27 is secured to a shaft 28, to which is 100 secured at its opposite end a short lever 29, having one of its ends engaged by a spring 30 and adapted to be moved in opposition to the spring 30 by means of a crank arm 31 formed integrally with a rotatably mounted 105 sleeve 32, the latter being mounted on a pivot pin 33, preferably screwed into the plate 34 of the needle bed. Also integrally formed with each sleeve 32 is another crank arm 35 on the opposite end to that on which the 110

crank arm 31 is formed, said crank arm 35 being adapted to be operated by means of a lever 36 (see Fig. 12), the lever 36 being provided with a slotted end 37 which slides over the crank arm 35, the lever 36 being automatically controlled by means of a cam ring 38, mounted adjacent to the rotary pattern cylinders 11. The lever 36 normally has its slotted end 37 kept in an upper position by means of a spring 39 secured to the lever and to a stationary part of the needle bed.

From the preceding description, it will be apparent that the bar 16 to which are secured the knitting cams, is automatically raised and lowered through the instrumentality of the wheel 23, which in turn is automatically controlled through interposed mechanism by the cam rings 38 located on opposite ends of the pattern cylinders. Pivotally mounted on each block 18 are two members 40 and 41 forming the projecting and retracting or knitting cams for operating the needle jacks 42. Each of these members 40 and 41 is provided at its free or outer end with a pin 43, which is slideable vertically up and down loosely in a hole 44 in an adjusting bar 45, slideable transversely of the cam bar 15 in a slot 46. Each of these bars 45 is secured to an adjusting bar 47, which is slideable in and guided by the adjusting bar guide 48. The adjusting bar guide 48 is carried by a pivotally mounted adjusting bar guide support 49, the latter having an arm or projection 50 formed integrally therewith normally held down by a spring 160 and in the outer end of which are adjustably mounted adjusting screws 51 which bear on pivotally mounted lever arms 52 that are operated by means of cam rings 53 mounted on one end of the rotary pattern cylinder 11. From the preceding description, it will be seen that the free ends of the members 40 and 41 of the projecting and retracting cams are automatically moved closer together or separated by the pivotal movement of the adjusting bar guide 48, in which slides the adjusting bar 47, to which are secured the plates 45 slideable transversely of the cam bar 15. By turning the adjusting screw 51, the amount of adjustment of the members of the cam may be varied as desired, to thereby vary the length of the loop formed by the knitting needles.

By referring to Fig. 13, it will be seen that each jack 42, to which is secured a needle 54, is provided with a pair of spaced, upwardly projecting nibs or cams 55 between which the members 40 and 41 of the cam pass to positively project and retract the jack. Each of these jacks 42, as is well understood, is mounted between division plates 56, and when in a retracted position, is adapted to be depressed by means of a jack operating lever 57, controlled from the

pattern cylinder in a well known manner. In order to provide means for holding each jack 42 in its retracted position when the same is not in operation, I provide a stationary projection 58, which is preferably formed by stamping out a portion from each division plate 56, and which is adapted to engage in a notch 59 on the under side of each jack 42 at its inner end.

By referring to Fig. 14, it will be seen that the member 41 of the cam which is traveling in the direction indicated by the arrow *a*, is provided with a main retracting portion 60 which will retract the jack from the position shown at *b* to that shown at *c*, and has an intermediate or inactive portion 61 and a short active face 62 oppositely arranged to the portion 60, which will project the jack slightly to the position *d* after the same has been retracted to its rearmost position *e*. The member 41 is furthermore provided with a sharp pointed end 63 adapted to enter between the nibs 55. The structure shown in Fig. 14 and just described, relates to the member 41 of the cam, but as will be obvious, the member 40 of the cam is similarly constructed and the members 40 and 41 act alternately as projecting and retracting cams in the motions back and forth across the needle bed.

It has heretofore been customary in knitting machines of the class to which this invention relates, to raise the projecting cam only out of action when not operating, the retracting or knitting cams being always in knitting position. In such a structure, the knitting point of the cams rub against the operating nib of the jack when the latter is not operating, for instance, when the knitting is done on the opposite side of the machine, and as will be apparent, this causes an unnecessary amount of wear, both on the cam and on the jacks. Another defect in knitting machines as ordinarily made, results from the knitting point of the cam striking the jack, which causes the latter to be slightly projected or retracted, which, in turn causes the loop to slip off of the hook on the needle, thus making imperfect work. By providing the mechanism which I have described, both the projecting and the retracting portions of the cam are moved simultaneously out of action when not required, thus preventing the unnecessary wear of the cam and also preventing any movement of the needles when the projecting cam is out of operation.

By providing each jack with a recess or projection adapted to engage the projections on the corresponding division plates, the jack and needle are positively prevented from being drawn forward by the stress of the yarn when the jack is not in operation.

I have described one form of my invention, but it will be obvious that many

changes and variations in the details thereof may be made without departing from the spirit of the invention, and all such changes and variations are contemplated as fall within the scope of the appended claims.

I claim:—

1. In a machine of the class described, in combination, knitting needles, jacks therefor, a cam bar and a cam for operating said jacks, said cam comprising two members pivotally mounted on and carried by said bar and mechanism for simultaneously adjusting the members of the cam, comprising a pair of plates slidably mounted on the cam bar, each of said plates being loosely pivoted to the free ends of the cam members.

2. In a machine of the class described, in combination, knitting needles, jacks therefor, a cam bar and a cam for operating said jacks, said cam comprising two members pivotally mounted on and carried by said bar, and mechanism for simultaneously adjusting the members of the cam, comprising a pair of plates slidably mounted on the cam bar, each of said plates being loosely pivoted to the free ends of the cam members, and an adjusting bar to which said plates are secured, said bar being longitudinally movable in unison with the cam bar.

3. In a machine of the class described, in combination, knitting needles, jacks therefor, a cam bar and a cam for operating said jacks, said cam comprising two members pivotally mounted on and carried by said bar and mechanism for simultaneously adjusting the members of the cam, comprising a pair of plates slidably mounted on the cam bar, each of said plates being loosely pivoted to the free ends of the cam members, and an adjusting bar to which said plates are secured, said bar being longitudinally movable in unison with the cam bar, an adjusting bar guide in which said adjusting bar reciprocates, said guide being movably mounted on the machine and a cam for controlling the movements of the guide.

4. In a machine of the class described, in combination, knitting needles, jacks therefor, a cam bar and a cam for operating said jacks, said cam comprising two members pivotally mounted on and carried by said bar, and mechanism for simultaneously adjusting the members of the cam, comprising a pair of plates slidably mounted on the cam bar, each of said plates being loosely pivoted to the free ends of the cam members, and an adjusting bar to which said plates are secured, said bar being longitudinally movable in unison with the cam bar, an adjusting bar guide, means for automatically moving the guide, and an adjusting device to change the movements of said guide.

5. In a machine of the class described, in

combination, knitting needles, jacks therefor, a cam bar, a cam carrying bar pivotally mounted on said cam bar having secured adjacent its free end a knitting cam adapted to operate the jacks and needles, a spring for normally holding the free end of the carrying bar raised, a stop for limiting the upward movement of the free end of the carrying bar, and means for depressing and retaining depressed the free end of the carrying bar, comprising a ratchet hub rotatably mounted on the cam bar, said ratchet hub being provided with a plurality of cam faces adapted to engage the carrying bar, pivoted dogs located at the ends of the needle bed for operating said ratchet hub and automatically controlled means for moving the dogs.

6. In a machine of the class described, in combination, knitting needles, jacks therefor, and a cam for operating said jacks, said cam comprising two members movably mounted relatively to each other, the cam being provided with one portion adapted to project the jacks and needles to their extreme forward position, another portion adapted to retract the jacks and needles to their extreme rear position and a third portion adapted to project the jacks and needles a slight distance forwardly immediately after the latter have been retracted.

7. In a machine of the class described, in combination, knitting needles, jacks and a knitting cam for operating said jacks, said cam comprising two members movably mounted relatively to each other, and movable to an inoperative position, each of said jacks being provided with a pair of spaced, operating nibs between which the cam is adapted to pass.

8. In a machine of the class described, in combination, knitting needles, jacks therefor, and a knitting cam for operating said jacks, said cam comprising two members movably mounted relatively to each other and having portions adapted to project the jacks to their innermost or forward position to retract the jacks and needles to their rear position, and to project the jacks slightly forward after they have been retracted, and each of said jacks being provided with a pair of spaced operating nibs between which the cam is adapted to pass.

9. In a machine of the class described, in combination, knitting needles, jacks therefor and a knitting cam for operating said jacks, said cam comprising two members movably mounted relatively to each other and adapted to be moved to an inoperative position relatively to the jacks, said cam having portions thereon adapted to project the jacks to their forward position, to their rear position and to a position slightly forward after they have been retracted, each of said jacks being provided with a pair of

1 spaced operating nibs between which the cam is adapted to pass.

10. In a machine of the class described, in combination, knitting needles, jacks, a 5 cam bar and a knitting cam carried by said cam bar, each of said jacks being provided with a pair of spaced operating nibs adapted to be engaged by the cam, said cam having portions thereof adapted to project and 10 retract the cams to their forward and rear positions, and having also a third portion adapted to slightly project the jacks after the latter have been retracted.

11. In a machine of the class described, in 15 combination, knitting needles, jacks, a cam bar and a knitting cam carried by said cam bar, each of said jacks being provided with a pair of spaced operating nibs adapted to be engaged by the cam, said cam having portions thereof adapted to project and retract 20 the cams to their forward and rear positions and having also a third portion adapted to slightly project the jacks after the latter have been retracted, and means for mov-

ing said knitting mechanism from an operable to an inoperable position and vice versa. 25

12. In a machine of the class described, in combination, knitting needles, jacks therefor and a knitting cam, said knitting 30 cam being movable from an operative to an inoperable position, and each of said jacks being provided with a pair of spaced operating nibs between which the cam is adapted to pass. 35

13. In a machine of the class described, in combination, knitting needles, jacks therefor and a knitting cam, said cam being movable from an operative to an inoperative 40 position and vice versa, and having portions thereof adapted to project and retract the jacks and also a third portion adapted to slightly project the jacks after the latter have been retracted.

WILSON W. BURSON.
